UNITED STATES PATENT OFFICE.

WILLIAM L. MERSFELDER, OF CINCINNATI, OHIO, ASSIGNOR TO HARDWICK STOVE CO., OF CLEVELAND, TENNESSEE.

DESIGN FOR A HEATING-STOVE.

SPECIFICATION forming part of Design No. 36,158, dated December 9, 1902.

Application filed November 3, 1902. Serial No. 130,006. Term of patent 7 years.

To all whom it may concern:

Be it known that I, WILLIAM L. MERSFELDER, a citizen of the United States, and a resident of the city of Cincinnati, in the county of Hamilton and State of Ohio, have invented and produced a new, original, and ornamental Design for a Heating-Stove, of which the following is a specification.

On the accompanying sheet of drawing, making a part of this specification, there is shown in perspective a heating-stove illustrating my design.

The leading feature of the design is that portrayed upon the side of the stove—namely, there is a central annular ornament adapted to inclose the shield or name plate on which the name of the stove or the name of the maker or the names of both can be located. Above this annular ornament is a design consisting of stems terminating in knobs disposed as shown and imparting the imaginative impression of a shell. The ends of the annular ornament where it meets the shell are incurved, thereby adding to the variety of the design and increasing the harmony of the adjacent parts. From the upper central shell-like figure there extends toward the ends of the side plate a series or bunch of what may be said to somewhat resemble petals, one bunch at each side of the shell. The origin or part from which these petals extend is near the shell. Although I have called these branches or stems which enlarge at the end "petals," they are not truly such, but are altered from what may be found in nature and have been made to assume a conventional and original shape. A portion of these stems extend out and reach near the ends of the plate, while others stop short thereof and others curve inwardly and some reach and some come near to the annular ornament. The ends of these branches are incurvate and enlarge at the curves, thereby increasing the variety of the design.

Below the horizontal center of the stove, on each side of the annular ornament and also below it, are located scroll-figures of an in-

tentionally irregular form. The stem of each figure begins in a knop below the annular ornament and curving downward and then upward and toward the adjacent end of the plate, and near this end curves over and down and then back and upward, leaving an enclosed space in which is a rosette. The latter fills this space otherwise blank and relieves the impression that the curved petals constitute the only ornament. From the curved main branch already described of this figure there ramify in pleasing curves other lesser branches, some of which apparently fill the lower portion of the plate near its ends, and the others extend upward and ornament the space near the lower half of the central annular ornament. One of the sub-branches of this figure crosses the main branch and recurses and divides, thus breaking the otherwise tedious long line of the main branch. Several minor petals are disposed upon the annular ornament and break the monotony of its conformation.

The entire design is very pleasing and attractive. All of the parts are disposed to lead the eye of the beholder toward the central portion of the plate, whereon a name or names can be located, and the entire design may be said to emphasize this center.

One subordinate feature of the design is the ornamentation, as shown, on the top plate.

Another subordinate feature of the design is the ornamentation, as shown, of the legs.

Another subordinate feature of the design is illustrated upon the front end of the stove.

Having described my invention, what I claim as new, and desire to secure by Letters Patent, is—

The ornamental design for a heating-stove, as herein shown and described.

In testimony whereof I have signed my name to this specification in the presence of two subscribing witnesses.

WILLIAM L. MERSFELDER.
